UNITED STATES PATENT OFFICE.

ANTON ZEMAN, OF PHILADELPHIA, PENNSYLVANIA.

COMBINED WINDOW SCREEN AND VENTILATOR.

1,318,253.

Specification of Letters Patent.

Patented Oct. 7, 1919.

Application filed April 12, 1918. Serial No. 228,219.

To all whom it may concern:

Be it known that I, ANTON ZEMAN, a subject of the Emperor of Austria-Hungary, (Czechs) residing at 3441 N. Hutchinson 5 street, Philadelphia, in the county of Philadelphia and State of Pennsylvania, have invented new and useful Improvements in Combined Window Screens and Ventilators, of which the following is a specification.

10 The invention relates to windows and window-ventilating devices, and has for an object to provide a combined screen and ventilator.

15 The invention comprehends among other features, the provision of a device that may be constructed in conjunction with the construction of a window, or which may be conveniently attached to any finished window, and which embodies an arrangement per- 20 mitting of effective ventilation into the room, and also supplying a screen, whereby the opening to the atmosphere can be screened to prevent the incoming of any insects, flies, mosquitoes or the like, the screen 25 of course being of any desired mesh, and in fact, being capable of being made of a very fine mesh to exclude any dust or dirt. Still further, the invention comprehends a device that will present a neat and effective 30 appearance when applied to a window, and in which the screen can be used alone when desired, or the ventilator alone, or the two can be used in combination, as will be hereinafter more fully set forth.

35 My invention still further embodies various improvements in window devices of the character set forth, over my Patent #1181499, granted to me May 2, 1916.

40 In the further disclosure of the invention, reference is to be had to the accompanying drawings, constituting a part of this specification, in which similar characters of reference denote corresponding parts in all the views, and in which—

45 Figure 1 is a fragmentary front elevation of a window showing my device applied thereto.

Fig. 2 is a vertical transverse sectional view taken through the structure shown in 50 Fig. 1.

Fig. 3 is an elevation of one of the adjustable brackets for the ventilator, and

Fig. 4 is an elevation of a modified form thereof.

Referring more particularly to the views, 55 the numeral 10 indicates a window, comprising the usual sill 11 and side frame or casing 12, with a sash 13 mounted to slide therein, the same being the lower sash, the sash, furthermore, having on its lower bar 60 14 the usual metallic or other handle 15, whereby the window sash can be raised or lowered. Arranged upon the sill 11 is a horizontally disposed casing 16 having side uprights 17 forming guides 18, and mounted upon each upright 17 is a relatively stationary bracket 19.

The casing 16 contains a spring-engaged shade roller 20 on which is wound a curtain 21, which projects up through a slot 22 in the casing, and can be pulled out as shown, the casing furthermore, having a second shade roller 23 mounted therein, and on which is wound a screen 24 adapted to pass through a slot 25 in the casing. A 70 releasing handle 26 is arranged to project through a slot 27 in the casing, said handle being connected with a spring pressed pawl 27^a engaging a ratchet 27^b on the roller 23 in order to release the pawl when the screen 80 thereof is in open position, so that the spring of the roller will wind up the screen on the roller, and return the screen into the casing. It being understood that the rollers 20 and 23 are of the usual spring type such as the ordinary shade roller, except that the roller 20 is constantly acted upon by the tension of the spring to exert a constant pull on the curtain 21; whereas, the roller 23 may be provided with a pawl and ratchet 90 lock, so that when the screen 24 is pulled out and extended, it will be locked in that position until the roller is released by the action of the handle 26, whereby the spring operating on the roller will return the screen 95 into the casing.

The ends of the device are of a fan-like nature and each comprises a main arm 28 pivotally connected at 29 with the bracket 19 and having slidably connected therewith 100

an arm 30, the upper end of which is provided with a notch 31 within which is engageable a rod 32 carried by the upper extremity of the curtain 21. Pivotally connected with the upper end of the arm 28, as shown at 33, is one end of a link 34 which has its other end provided with a clamping bolt 35 slidably engaged within a vertical slot 36 formed in the bracket 19. Pivotally connected with the link 34, as shown at 37, is a series of slats 38 which have their other ends pivotally connected, as shown at 39, with the arm 28. The arm 28 is provided with a longitudinally extending slot 40 through which extend the pivots 39.

In the use of my device, we will assume that it is desired to raise the window sash 13 a distance for the purpose of ventilation, and in doing so it is desired that the opening formed by the raising of the window be screened to prevent insects from coming into the room, and that the ventilation will be such as will not cause a draft into the room, and further help to keep out any inclement weather, such as rain, sleet or snow; to accomplish the result a ring 41 is attached to the center of a rod 42 connected to the upper end of the screen 24, with the ends of the rod operating in the guides 18, and this ring is attached to the handle 15 of the window sash, either before or after the window is raised, thus causing the screen to be pulled out of the casing to cover the opening made by the raising of the window sash. The sides or bracket supports of the ventilator are now swung into open position to form end closures, as it were, and the ventilating curtain can now be pulled out of the casing and the ends of the rod 32 will be looped over and arranged upon the seats 31 of the end closures or bracket supports. With this construction it will be seen that the window will now have its opening screened to prevent the intrusion of any insects or the like, and effective ventilation will be provided by the ventilating part, including the end closures and curtain, so that a direct draft cannot come into the room, and the air entering a room will be actuated upwardly rather than directly inward on a horizontal plane. It will of course be understood that should it be desired to use the screen by itself, this can readily be accomplished by leaving the end closures in folded position and the curtain within the casing, and vice versa, the ventilating curtain can be raised into open position to repose upon the previously opened brackets, and be supported thereby, while the screen can be left in the casing, so that the opening formed by the raising of the window sash will not be covered.

In the above referred to operation of pulling the ends of the device into extended

position, it will be observed that downward movement of the clamping bolt 35 within the slot 36 will cause the arm 28 carrying the arm 30 to be swung outwardly away from the bracket 19, the slot 40 in the arm 28 permitting the slats 38 to adjust themselves properly. It will therefore be observed that the angular inclination of the curtain 21 when its rod 32 is engaged within the notches 31, may be readily varied so that the air entering through the window may be deflected upwardly at variable inclines. It will also be observed that the slidable adjustability of the arm 30 upon the arm 28 permits upward extension of the curtain 21 to a greater or less extent.

Referring to the modified form shown in Fig. 4, it will be seen that the ends of the device are formed from a plurality of slats 43 pivotally connected, as shown at 44 and having their upper ends connected by pins 45 riding within slots 46 whereby the slats may be extended or folded, as desired. The outermost slats in this form are provided at their upper extremities with notches 47 within which the rod 32 upon the upper end of the curtain 21 may be engaged. This form is not capable of the adjustment which may be made with the preferred form though the slats may be folded to occupy but little space or extended to form end closures for the ends of the device.

It will of course be understood that I do not limit myself to the particular construction set forth in the drawings; that various slight changes may be made from the description and drawings without departing from the spirit of the invention, the scope of which is defined in the appended claims.

I claim:

1. In combination with a window frame and a sash slidable therein, a horizontally disposed casing on the sill of the window, a spring roller within said casing, a curtain wound upon said roller and normally contained within said casing, vertically extending brackets connected with said casing and provided with vertical slots, a pair of arms pivotally connected at their lower ends with said brackets, links pivotally connected with the upper ends of said arms and having their other ends provided with clamping bolts slidable within said slots, the upper ends of said arms being adapted for engagement with and retention of the free edge of said curtain.

2. In combination with a window frame, a casing secured thereon, upstanding brackets connected with said casing and provided each with a vertical slot, an arm pivotally connected at its lower end with each bracket, a second arm slidable upon each of said first named arms and having its upper end provided with a notch, a link pivotally con-

nected with the upper end of each of said first named arms, a clamping bolt at the other end of each link slidable through said vertical slot in the associated bracket, each of said first named arms being provided with a longitudinally extending slot, a plurality of slats pivotally connected at their upper ends with said link and having their

lower ends pivotally and slidably connected within said last named slot, a spring roller 10 journaled within said casing, a curtain wound upon said roller, and a rod upon the free end of said curtain and engageable within said notches.

In testimony whereof I affix my signature. 15
ANTON ZEMAN.
